[57] CLAIM

The ornamental design for shooting game cabinet, as shown and described.

DESCRIPTION

FIG. 1 is a front elevational view of a shooting game cabinet showing our new design;

FIG. 2 is a rear elevational view thereof;

FIG. 3 is a top plan view thereof;

FIG. 4 is a bottom plan view thereof;

FIG. 5 is a right side elevational view thereof; the left side elevational view being a mirror image thereof;

FIG. 6 is a front and left side perspective view thereof;

FIG. 7 is a rear and right perspective view thereof; and

FIG. 8 is a front and right side perspective view thereof; with the targets shown in alternate position and right side net removed for ease of illustration.
